MILK BOTTLE HOLDER AND THE LIKE

Alphonse Chalifoux, Montreal, Quebec, Canada

Application October 24, 1935, Serial No. 46,558

3 Claims. (Cl. 232—42)

My invention relates to a door locker for milk bottles and other articles.

An object of my invention is to provide a container or receptacle adapted to be secured at a door of one's home and to receive milk bottles and other articles, so that these may be safe from theft and protected from dirt until such time as the householder brings the same into the house.

Another object is to so build the device that the closure is normally unlocked to permit of the milkman or other person making delivery of the article, to deposit the article into the device without the necessity of unlocking the same, the closure locking automatically after the bottle or other article has been deposited within the device.

Another object is to build the device to as simple a construction as possible by leaving, for instance, the rear side open whereby access may be gained into the device by the householder without having to open any closure other than the house door.

Another object is to attach the device to the door in a simple but safe manner whereby, when desired, it may be lifted bodily and taken into the house.

Other objects will appear as the specification is read in the light of the drawing.

In the drawing, wherein like numerals of reference indicate corresponding parts in the various figures,

Figure 1 is a more or less diagrammatic view illustrating the application of my device, the house door shown being now open to gain access into the device;

Figure 2 is a plan cross section of the device;

Figure 3 is a section taken on line 3—3 in Figure 2.

Figure 4 is a cross section on line 4—4 in Figure 2.

Figures 5 and 6 are fragmentary perspective views respectively of the brackets securing the device to the door frame.

Referring now by numerals to the drawing, 10 indicates my device, which comprises essentially a container, preferably partly semi-circular in cross section, open at the rear and provided with a front opening which is closed by a (preferably automatically closing) revolving door; and a 20 platform to receive the milk bottles or other articles to be deposited in the device, which platform, when loaded, operates to automatically lock the door of the device, after the door has been closed.

As shown, the container proper 11 is formed

with a semi-circular front wall 12 having an opening 13, side walls 14, a top wall 15, and a bottom wall 16. The container is thus open at the rear as at 17, whereby access may be gained into the container from the rear. Within the 5 container is the revolvable door 18 curved to substantially the inside radius of the curved front wall 12, and adapted to effectively close the opening 13. This door or closure 18 has upper and lower bent-in portions 19 spaced to lie adjacent 10 the top and bottom walls 15 and 16, respectively, of the container, and extending to and beyond the centre of the semi-circular front wall 12. These portions are perforated near the inner ends 15 to receive bolts 20 passed through the upper and lower walls 15 and 16, these bolts constituting pivots revolvably mounting the door or closure 18 within the container proper as aforesaid. A sleeve 36 may be provided below the lower bent-in portion 19, this sleeve surrounding the bolt 20 20 and forming a support for the door 18.

Fixed at either end to the door 18, or more particularly to the bent-in portions 19, and to the container proper, respectively, are springs 19A tensioned to normally urge the door to a certain or closed position, the closed position of the door being determined by the engagement of a stop 20A (which may form the door opening means or knob) with the container proper, at one side of the opening 13. The springs will 30 thus yieldingly resist an opening movement of the door, while when released, they will act to automatically close the door.

Within the container proper is the platform 23 which receives the milk bottles or other articles 35 as aforesaid. This platform may take the form of a semi-circle, and it is pivotally mounted to the container as with a suitable hinge 24. Mounted below the platform is a tensioned spring 25, one end being fixed to the container, while 40 the other, or free end, loosely engages the lower face of the platform. This spring urges the free end of the platform in an upwardly direction. The tension in this spring is such that it will be overcome by the weight of the platform when 45 loaded. The upward swinging movement of the platform under the action of the spring 25 is determined by a member or stop 26 which is fixed to the container. Fixed to the underside of the platform is a pin 27 positioned to ride on the 50 lower bent-in portion 19 of the door 18 when the same is open or partly open, the pin clearing this portion to lie and be substantially engaged by one edge of the bent-in portion when the door is closed. Thus, the pin serves as a means of lock- 55

ing the door in its closed position when a bottle or other article has been deposited upon the platform. Upon the removal of the article, the platform rises under the action of the spring 25, the 5 pin 27 clears the edge of the platform or bent-in portion 19, and permits of the door or closure 18 being opened by the knob 20.

The device may be secured to the door frame, or more particularly to the stile nearest the 10 house door hinges, as by suitable brackets as shown. A bracket member 30 is secured to the stile as with, say screws, while a co-operating bracket member 31 is secured to one side wall of the container. The member 30 is formed at the 15 bottom with a turned-up hook or lug 32, and intermediate its length, with a bent-out portion 33. The bracket 31 is formed with laterally turned lugs or prongs 34 and 35 adapted to fit between the turned-up lug 32 and the main body of the 20 member 30, and into the bent portion or keeper 33 formed on the member 30, respectively. The co-operating or locking brackets 30 and 31 are unlocked, and can only be so unlocked by moving the member 31 in one direction, that is, in a rear- 25 wardly direction or in the direction of the house door. Therefore, by securing the member 30 to the door stile which is nearest the house door hinges, and placing the same so that the rear of the container proper is almost in contact with 30 the house door when closed, it follows that the device cannot be removed until the house door is fully opened. Similarly, the device can only be placed into operative position by fully opening the house door.

35 *Operation.*—When the device is empty, the platform 23 is in its raised position, engaging the hook 26. The pin 27 is now raised above the level of the lower bent-in portion 19, so that the door or closure 18 is now free to open. When it is 40 desired to deposit a milk bottle or other article within the container, the person effecting delivery opens the closure by means of the knob 20, deposits the article and then releases the closure. The platform will now be lowered under the 45 weight of the bottle or article, the pin 27 bearing upon the lower bent-in portion 19. As the door is released, the same will automatically swing back into its normal or closed position under the action of the springs 19A, if the resiliency thereof 50 is sufficient; or in any event, the door may be closed by the knob 20. Upon the door reaching its closed position, the platform will descend and thereby bring the pin 27 adjacent one edge of the

bent-in portion 19 and will now act as a lock against the opening movement of the door. When the householder desires to possess himself of the bottle or other article, he opens the house door and thus gains access into the container through 5 the rear opening 17. After the article has been removed from the platform, the same lifts automatically under the action of the spring 25, and the door or closure 18 is again free to be opened.

What I claim is:—

1. In a locker for milk bottles and other articles, a container having spaced openings, a closure for one of said openings having bent-in portions pivotably mounted to said containers, spring means urging said closure to its closed position, 15 a hinged platform for the bottles within said container, spring means urging said platform to a normally raised position, means determining the raised position of said platform, and means on said platform co-operating with one of said bent- 20 in portions of said closure and locking the same when in its closed position when said platform is lowered by the weight of the bottles.

2. In a locker for milk bottles and other articles, a container having a curved wall formed 25 with an opening, a curved closure within said container for closing the opening and having bent-in portions pivotably mounted to said container, spring means urging said closure to its closed position, a hinged platform within said 30 container for the bottles, spring means urging said platform to a normally raised position, means determining the raised position of said platform, and means on said platform cooperating with one of said bent-in portions of said closure and locking the same in its closed position when said platform is lowered by the weight of the bottles.

3. In a locker for milk bottles and other articles, a container having a curved wall formed with 35 an opening, a curved closure within said container for closing the opening and having bent-in portions pivotably mounted to said container, means urging said closure to its closed position, a hinged platform within said container for the bottles, means urging said platform to a nor- 40 mally raised position, means determining the raised position of said platform, and means on said platform co-operating with one of said bent-in portions of said closure and locking the same in its closed position when said platform is low- 45 ered by the weight of said bottles.

ALPHONSE CHALIFOUX.
